DESIGN FOR A SHOE

Pedro J. Nicolau, Lewiston, Maine

Application January 21, 1935, Serial No. 54,956

Term of patent 3½ years

To all whom it may concern:

Be it known that I, Pedro J. Nicolau, a citizen of the United States of America, residing in Lewiston, county of Androscoggin, and State of Maine, have invented a new, original, and ornamental Design for a Shoe, of which the following is a specification, reference being had to the accompanying drawing, forming part thereof, wherein,

I claim:

The ornamental design for a shoe, substantially as shown.

PEDRO J. NICOLAU.
